UNITED STATES PATENT OFFICE

WALTER W. LANDSIEDEL, OF CINCINNATI, OHIO, ASSIGNOR TO REMINGTON RAND INC., OF BUFFALO, NEW YORK, A CORPORATION OF DELAWARE

ADJUSTABLE CONTROL CAM

Application filed October 1, 1927. Serial No. 223,438.

This invention relates to function control cams carried by the carriage of the well-known Dalton adding machine.

An object of this invention is the provision of a control cam which can be readily adjusted on its cam bar.

Another object is the provision of a readily adjustable control cam for closely spaced rectangular cam bars.

10 Another object is to provide an adjustable control cam which is simple in design and inexpensive to manufacture.

Other objects and advantages will appear from the description taken in connection 15 with the drawings in which:—

Fig. 1 is a side view of a control cam.

Fig. 2 is an end view of a control cam.

Fig. 3 shows a control cam assembled on a cam bar.

20 Fig. 4 is a diagrammatic view of an assembly of cam bars and a possible arrangement of the control cams.

The control cam 10 comprises a main body portion which, as shown in Figs. 1 and 3, is 25 substantially rectangular in form. The lower edge of the cam is provided with wedge surfaces 11 cooperable with mechanism for controlling the functions of the machine as the carriage in which the cams are mounted 30 is shifted laterally.

The carriage and the mechanism cooperating with the control cam have not been shown as this invention relates solely to the construction of the control cams and their connection with the cam carrying bars.

35 The upper edge of the control cam 10 is bent laterally as at 12 and then downwardly to provide a portion 13 which together with the upper portion of the main body of the cam forms a U in which is housed a spring 14 suitably anchored on a stud riveted in the main body and projecting loosely through the portion 13.

40 As shown in Fig. 3, the control cam is mounted on a bar 15, the upper edge of which lies within the U by means of which the cam is locked to the bar against removal laterally of the bar. The ends of the spring 14 bear 45 on the upper edge of the bar and constantly

urge the cam upwardly for a purpose about to be disclosed.

The lower end of the control cam is held against removal laterally of the bar by a laterally offset tongue 16 on a plate 17 spot welded or otherwise rigidly secured to the lower portion of the main body of the cam. The lower edge of the plate 17 is provided with wedge surfaces of the same inclination as the surfaces 11 and which in effect constitute a continuation thereof, thereby providing a fairly wide bearing. In this way, the extra width added to the cam is located under the cam bar, thereby not interfering with the close spacing of the cam bars, (see 65 Fig. 4).

The upper edge of the plate 17 is provided with teeth 20, (Fig. 1), cooperating as shown in Fig. 3 with teeth 21 on the lower edge of the cam bar 15. As is obvious from Fig. 3, 70 the control cam 10 is held in its adjusted position on the bar by the teeth 20 and 21 which are held inter-engaged by the spring 14. The cam can be moved into any other position after freeing it from the teeth by downward 75 pressure on the cam applied by the hand or any suitable means. Upon release of the pressure, the teeth 20 will be drawn into engagement with the teeth 21 by the spring 14 to hold the cam securely in its new position 80 of adjustment.

It is obvious that by increasing the number of teeth per inch on the control cam and the cam bar, a relatively fine adjustment of the cam on the bar can be made if necessary. 85

As seen in Fig. 3, the upper edge of the plate 17 has a long bearing on the lower edge of the cam bar 15 which provides a safeguard against tilting movement of the control cam about an axis transverse of the bar. 90 This is also augmented by the spaced bearing ends of the spring 14.

It is apparent from Fig. 4 that the bars 15 may be closely spaced if desired, in fact, so close that adjacent cams of adjacent 95 bars may be placed in actual contact with each other, or cams on one bar may contact with adjacent bars. This is made possible because of the general construction of the cam embodying a relatively large body por- 100

tion of relatively thin material and by using the lower edge of the plate 17 as parts of the cam surfaces.

While a preferred form of embodiment of the control cam and bars has been shown and the advantages thereof explained, it is obvious that other forms of embodiment of the invention may be made within the terms of the claims.

10 I claim as my invention:—

1. A control cam comprising a main body portion having one of its sides bent back upon itself to form a **U** adapted to embrace a cam bar, and a spring stud anchored in said main body portion and projecting into said bent back portion.

2. A control cam comprising a main body portion having one of its sides bent back upon itself to form a **U** adapted to embrace a cam bar, a spring stud anchored in said main body portion and projecting into said bent back portion, and a spring anchored on said stud and having spaced free end bearing portions.

25 3. A control cam comprising a main body portion having one of its edges bent back upon itself to form a **U** and its other edge constituting a cam, and a rack member secured against one side of said main body portion and lying in the plane of the opening of the **U**.

4. A control cam comprising a main body portion, a rack engaging member secured against one side of the main body portion, and a laterally offset guide lip on said rack 35 engaging member.

5. A control cam comprising a main body portion, one edge of which is bent back to form a **U**-shaped channel to receive one edge of a cam bar, a cam bar engaging plate secured to the opposite edge of the main body portion, and an offset portion on said plate forming a **U**-shaped channel with the main body portion to receive the opposite edge of the cam bar.

45 6. A control cam comprising a main body portion, one edge of which is bent back to form a **U**-shaped channel to receive one edge of a cam bar, a plate secured to the opposite edge of the main body portion and adapted 50 to bear against the opposite edge of the bar, an offset portion on said plate adapted to bear against the side of the bar, and a spring within said **U**-shaped channel adapted to bear against the first mentioned edge of the bar.

55 7. A control cam comprising a main body portion adapted to have one of its sides contact with the side of a cam bar, and a cam member secured to said side of the main body portion to lie in the plane of said cam bar.

60 8. A control cam comprising a main body portion adapted to have one of its sides contact with the side of a cam bar, and having 65 one of its edges provided with cam surfaces,

and a plate secured to said side of the main body portion and provided with cam surfaces in the same planes as said cam surfaces on the control cam.
